UNITED STATES PATENT OFFICE.

LEWIS H. JOHNSON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,306,063.

Specification of Letters Patent. Patented June 10, 1919.

Application filed January 2, 1918. Serial No. 209,970.

To all whom it may concern:

Be it known that I, LEWIS H. JOHNSON, a citizen of the United States, residing at Bloomfield, in the county of Essex, State of New Jersey, have invented certain new and useful Improvements in Telephone Systems, of which the following is a full, clear, concise, and exact description.

This invention relates to telephone exchange systems and more particularly to such systems in which connection is to be established between a telephone line terminating at a manual exchange and a telephone line terminating at an automatic exchange.

The principal feature of the invention resides in the provision of means for preventing the false operation of automatic control apparatus at the automatic exchange end of the trunk circuit when connection is made therewith at the manual exchange.

Other features which result from or are incident to the main object above noted will appear during the description of the invention.

One embodiment of this invention is illustrated in the accompanying drawing which shows a telephone line A extending to a manual exchange or central office, and there connected in any well-known manner with the cord circuit B. This cord circuit B may be employed to connect the telephone line A with a trunk circuit C extending from the manual exchange to an automatic exchange, where it may connect with an automatic telephone line D terminating at the automatic exchange. The apparatus shown to the left of the dotted line 2, 2 is located at the manual exchange, while that shown to the right thereof is located at the automatic exchange. The apparatus for connecting the trunk circuit C with the automatic line D which is diagrammatically illustrated in the dotted rectangle 3 may be of the type disclosed in the Williams Patent No. 1,237,433. The apparatus shown to the right of the vertical dotted line in Fig. 1 and that shown in Fig. 2 of the Williams patent, with the exception of the automatic line may be connected with the three-conductor trunk circuit C shown in the drawing of the present application, in which case the slow-release relay 14 and the rotary and vertical magnets 11 and 23 would be controlled over the control conductor 5 of the trunk circuit C.

Assuming that the subscriber A has initiated a call in the usual manner and that the cord circuit B has been connected therewith, the operator may actuate listening key 6 to connect the operator's telephone set therewith. Upon being advised that connection is desired with the line of subscriber D terminating at an automatic exchange, the operator may or may not actuate splitting key 7. The operator then inserts calling plug 8 of the cord circuit B into jack 9 of the trunk circuit C. Relay 10 is thereupon operated over a circuit from battery through resistance 11, contact 12 of relay 13, the winding of relay 10, sleeve contacts of the jack 9 and the plug 8, the winding of relay 14, contact 15 of the splitting key 7 and resistance 16 to ground, if the splitting key is not actuated; and if the splitting key is actuated, then through contact 17 of splitting key 7, calling dial 18 and resistance 19 to ground. The resistance 11 is high so that when included in circuit with relay 14, this relay does not attract its armature. The operation of relay 10 causes the lamp 25 associated with the jack 9 and the lamp 26 associated with jack 27 of the trunk circuit C to be lighted, the circuit therefor being from battery through the contact of relay 10, normal contact of relay 28, and through the lamps 25 and 26 and resistances 29 and 30 in parallel to ground. These lamps serve as busy signals. When the splitting key 7 is actuated, relay 35 is energized over a circuit from battery through the winding of relay 35, contact 36 of the listening key 6, and contact 37 of the splitting key 7 to ground. The energization of relay 35 connects impedance coils 38 across the tip and ring conductors of the cord circuit B, so that, upon the complete connection of the plug 8 with the jack 9, relay 40 is operated over a circuit from battery through the right-hand winding of relay 40, contact 41 of relay 13, tip contacts of the jack 9 and the plug 8, upper contact of the listening key 6, lower contact of relay 35, impedance coils 38, upper contact of relay 35, middle contact of the listening key 6, ring contacts of the plug 8 and the jack 9 and contact 42 of relay 13 to ground. Relay 40, in operating, causes the energization of a slow release relay 28 over a circuit from battery through the contact of relay 10, contact of relay 40 and the winding of relay 28 to ground. Re-

lay 28, upon attracting its armatures, substitutes battery through its left-hand contact for battery through its normal contact, for maintaining the lamps 25 and 26 lighted. By the closure of its right-hand contact, relay 28 causes the operation of relay 13 over a circuit which includes the left-hand winding of relay 40, so that relays 10, 13, 28 and 40 remain operated until the plug 8 is withdrawn from the jack 9. Relay 13 in operating disconnects the right-hand winding of relay 40 from the tip talking strand of the trunk circuit and removes ground from the ring strand thereof. Relay 13 in operating also closes the normally open contacts in the talking strands of the trunk circuit C. Contact 12 is opened, removing the high resistance 11 from circuit relation with relay 10, and contact 43 is closed, extending the control conductor 5 through to the automatic exchange where it may pass through the low resistance winding of relay 14 (see Williams Patent 1237433) and battery to ground. It is possible that relay 10 may be released during the short period between the opening of contact 12 and the closure of contact 43, but since relay 28 is made slow to release, relays 40 and 13 will remain energized during this period. Upon the closure of contact 43 relay 10 is then maintained energized, due to battery furnished from the automatic exchange over the control conductor 5. Due to the lower resistance path through the winding of the relay at the automatic exchange established upon the closure of contact 43, relay 14 of the cord circuit B operates, lighting the lamp 44. Upon observing the lighted condition of the lamp 44 the operator may operate the calling dial 18 to select the line of subscriber D. Each time that the contact of the calling dial 18 is opened relay 14 releases its armature so that the lamp 44 is intermittently lighted during the operation of the calling dial to furnish a signal to the operator. After the necessary operation of the calling dial to cause the establishment of a connection between the trunk circuit C and the line D, the operator may restore the listening key 6 and splitting key 7 to normal position, whereupon relay 35 is released. Relay 14 then remains energized over a circuit which includes the resistance 16 and consequently the lamp 44 remains lighted. Should the operator desire to supervise the connection, the actuation of the listening key merely connects the operator's telephone set across the talking circuit and has no effect upon the relay 35, since its circuit also includes the normally open contact of the splitting key 7. It will be noted from the above description that by maintaining the control conductor 5 open until after the plug 8 has been completely inserted into the jack 9, it

is impossible through any manipulation of the plug 8 to cause the false operation of the starting apparatus at the automatic exchange, thereby preventing a false selection.

What is claimed is:

1. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, electromagnetic means operated in response to the connection of the link circuit with the trunk circuit for closing the normally open control conductor, and a relay operating upon connection of the link circuit with the trunk circuit and serving to maintain the electromagnetic means in operated condition. 70

2. A telephone system comprising a trunk circuit including a normally open control conductor extending from a first to a second central office, a telephone line terminating at the second central office, switching apparatus thereat controlled over the control conductor from the first central office for est- 75

ablishing connection between the trunk circuit and the telephone line, a link circuit at the first central office, a relay operating over 80

portions of the trunk and link circuits upon connection of the link with the trunk cir- 85

cuit, a second relay for closing the normally 90

open control conductor, and an energizing 95

circuit for the second relay established by 100

the closure of a contact of the first relay. 105

3. A telephone system comprising a trunk circuit including a normally open control 110

conductor extending from a first to a second central office, a telephone line terminating at 115

the second central office, switching apparatus thereat controlled over the control conductor from the first central office for estab- 120

lishing connection between the trunk circuit and the telephone line, a link circuit at the first central office, a relay in the control conductor responsive to the connection of 125

the link circuit with the trunk circuit, a sec- 130

ond relay energized over a portion of the 135

talking circuit of the engaged link and trunk 140

circuits, a third relay responsive to the ener- 145

gization of the second relay to close the nor- 150

mally open control conductor, and a locking 155

circuit for the second relay controlled by 160

the first and established simultaneously with 165

the energization of the third relay. 170

4. A telephone system comprising a trunk circuit including a normally open control 175

conductor extending from a first to a second central office, a telephone line terminating at 180

the second central office, switching apparatus thereat controlled over the control conductor from the first central office for estab- 185

lishing connection between the trunk circuit and the telephone line, a link circuit at the first central office, a relay operating over 190

portions of the trunk and link circuits upon connection of the link with the trunk cir- 195

cuit, a second relay for closing the normally 200

open control conductor, and an energizing 205

circuit for the second relay established by 210

the closure of a contact of the first relay. 215

lishing connection between the trunk circuit and the telephone line, a link circuit at the first central office, a relay energized upon connection of the link circuit with the trunk circuit and over a portion of the talking circuit of the engaged link and trunk circuits, a second relay energized upon the energization of the first for closing the normally open control conductor and for disconnecting the first relay from the talking circuit, and a third relay for thereafter maintaining the second relay energized.

5. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, a relay in the trunk circuit having two windings and energized through one of its windings upon the connection of the link circuit with the trunk circuit, a second relay energized upon the energization of the first relay to close the normally open control conductor, and a locking circuit for the first relay including the second winding thereof established simultaneously with the energization of the second relay.

6. A telephone system comprising a trunk circuit including normally open talking and control conductors extending from a first to a second central office, a telephone line terminating at the second central office, switching apparatus thereat controlled over the control conductor from the first central office for establishing connection between the talking conductors of the trunk circuit and the telephone line, a link circuit at the first central office, a relay in the trunk circuit responsive to the connection of the link circuit with the trunk circuit, a second relay energized upon the response of the first relay for controlling the closure of the normally open talking and control conductors of the trunk circuit, and a locking circuit for the first relay established after the energization thereof.

7. A telephone system comprising a trunk circuit including normally open talking and control conductors extending from a first to a second central office, a telephone line terminating at a second central office, switching apparatus thereat controlled over the control conductor from the first central office for establishing connection between the talking conductors of the trunk circuit and the telephone line, a link circuit at the first central office, a relay normally connected with one of the talking conductors of the trunk circuit and energized over a portion of that conductor upon the connection of the link

circuit with the trunk circuit, a second relay energized upon the operation of the first relay to disconnect the first relay from the talking conductor and to close the normally open talking and control conductors, and a locking circuit for the first relay established simultaneously with the energization of the second relay.

8. A telephone system comprising a trunk circuit including a normally open control conductor extending from a first to a second central office, a telephone line terminating at a second central office, switching apparatus thereat controlled over the control conductor from the first central office for establishing connection between the trunk circuit and the telephone line, a telephone line terminating at the first central office, a link circuit thereat connected with the latter telephone line, an operator's telephone set at the first central office, a listening key for connecting the telephone set with the link circuit, a splitting key for opening up the talking conductors of the link circuit, an impedance coil, a relay operating upon the actuation of the listening and splitting keys to connect the impedance coil with a talking conductor of the link circuit, a relay in the trunk circuit energized over a path including the impedance coil upon the connection of a link circuit with the trunk circuit, and a second relay energized upon the energization of the first relay of the trunk circuit to close the normally open control conductor.

9. A telephone system comprising a trunk circuit including normally open talking and control conductors extending from a first to a second central office, a telephone line terminating at the second central office, switching apparatus thereat controlled over the control conductor from the first central office for establishing connection between the trunk circuit and the telephone line, a telephone line terminating at the first central office, a link circuit thereat connected with the latter telephone line, an operator's telephone set at the first central office, a listening key for connecting the telephone set with the link circuit, a splitting key for opening up the talking conductors of the link circuit, an impedance coil, a relay operating upon the actuation of the listening and splitting keys to connect the impedance coil with a talking conductor of the link circuit, a relay in the trunk circuit normally connected with a talking conductor thereof and energized over a circuit including a portion of the talking conductor and the impedance coil upon connection of the link circuit with the trunk circuit, a second relay energized upon the energization of the first trunk relay to disconnect the first relay from the talking conductor and to close the normally open talking and control conductors.

control conductors, and a locking circuit for the first relay established simultaneously with the energization of the second relay.

5. 10. A telephone system comprising a trunk circuit including a talking and a normally open control conductor extending from a first to a second central office, a telephone line terminating at the second central office, switching apparatus thereat controlled over the control conductor from the first central office for establishing connection between the trunk circuit and the telephone line, a link circuit at the first central office, a relay operating over a portion of the talking conductor upon connection of the link circuit with the trunk circuit for closing the normally open control conductor, and a relay controlled over the control conductor for thereafter maintaining the control conductor closed.
  10. 15. A telephone system comprising a trunk circuit including a pair of talking conductors, and a normally open control conductor extending from a first to a second central office, a telephone line terminating at the second central office, switching apparatus thereat controlled over the control conductor from the first central office for establishing connection between the trunk circuit and the telephone line, a link circuit at the first central office, and a relay operating over portions of the two talking conductors in series upon connection of the link circuit with the trunk circuit for closing the normally open control conductor.
  15. 20. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, and a relay operating over portions of the two talking conductors in series upon connection of the link circuit with the trunk circuit for closing the normally open control conductor.
  20. 25. A telephone system comprising a trunk circuit including a pair of talking conductors, and a normally open control conductor extending from a first to a second central office, a telephone line terminating at the second central office, switching apparatus thereat controlled over the control conductor from the first central office for establishing connection between the trunk circuit and the telephone line, a link circuit at the first central office, and a relay operating over portions of the two talking conductors in series upon connection of the link circuit with the trunk circuit for closing the normally open control conductor.
  25. 30. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, and a relay operating over portions of the two talking conductors in series upon connection of the link circuit with the trunk circuit for closing the normally open control conductor.
  30. 35. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, and a relay operating over portions of the two talking conductors in series upon connection of the link circuit with the trunk circuit for closing the normally open control conductor.
  35. 40. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, and a relay operating over portions of the two talking conductors in series upon connection of the link circuit with the trunk circuit for closing the normally open control conductor.

control conductor extending from a first to a second central office, a telephone line terminating at the second central office, switching apparatus thereat controlled over the control conductor from a first central office for establishing connection between the trunk circuit and the telephone line, a link circuit at the first central office, an operator's telephone set, a listening switch for connecting the operator's telephone set with the link circuit, and electromagnetic means responsive to the connection of the link circuit with the trunk circuit when the listening switch is operated for closing the normally open control conductor.

13. A telephone system comprising a trunk circuit including a normally open control conductor extending from a first to a second central office, a telephone line terminating at the second central office, switching apparatus thereat controlled over the control conductor from the first central office for establishing connection between the trunk circuit and the telephone line, a link circuit at the first central office, an operator's telephone set, a listening switch for connecting the operator's telephone set with the link circuit, a relay in the trunk circuit controlling the closure of the normally open control conductor, and an energizing circuit for the relay established upon connection of the link circuit with the trunk circuit and including a contact of the listening switch.

In witness whereof, I hereunto subscribe my name this 28th day of December A. D., 1917.

LEWIS H. JOHNSON.
